DESIGN FOR A HOOD FOR IRONING MACHINE OR THE LIKE

Roy A. Bradt, Newton, Iowa, assignor to The
Maytag Company, Newton, Iowa, a corporation
of Delaware

Application September 27, 1935, Serial No. 58,738

Term of patent 7 years

To all whom it may concern:

Be it known that I, Roy A. Bradt, residing at Newton, in the county of Jasper and State of Iowa, a citizen of the United States, have invented a new, original, and ornamental Design for a Hood for Ironing Machine or the like, of which the following is a specification, reference being had to the accompanying drawing, forming a part thereof.

Fig. 1 is a view in side elevation of a hood for ironing machine or the like showing my new design.

Fig. 2 is an end elevation thereof.

I claim:

The ornamental design for a hood for ironing machine or the like substantially as shown.

ROY A. BRADT.
